CHARLES SEAMAN, OF BROOKLYN, NEW YORK.

NEEDLE GUARD FOR SEWING MACHINES.

1,410,413.

Specification of Letters Patent. Patented Mar. 21, 1922.

Application filed March 16, 1920. Serial No. 366,282.

To all whom it may concern:

Be it known that I, CHARLES SEAMAN, a citizen of the United States, and a resident of the borough of Brooklyn, county of 5 Kings, and State of New York, have invented certain new and useful Improvements in Needle Guards for Sewing Machines, of which the following is a specification.

10 My invention relates to needle guards for sewing machines, and the main object of the invention is effectually to prevent the operator from getting her finger under the needle, and to accomplish this result without interfering with the usual normal operation of 15 the sewing machine. Heretofore, so far as I am aware, or have found in an extensive factory experience, no needle guard of a practical nature has been proposed or has 20 appeared upon the market. A more particular object of the invention is to provide such a guard device adapted for use upon different makes and types of sewing machines employing a variety of styles of 25 presser feet, sometimes four or five different styles of presser feet being employed upon a single machine. Other objects of the invention are to provide unobstructed vision and plenty of light on the work, together 30 with the effective guarding of the needle against the possibility of the finger of the operator getting in its path. Other objects are that the guard device be independent of the presser foot, to provide that the needle-guarding members may be moved away from 35 their needle-guarding position for access to the needle, but at the same time assuring their automatic return to the guarding position so as to prevent the possibility of the 40 needle being left unguarded. Other objects and advantages of my invention will herein-after appear.

45 My invention includes features of construction and combinations of parts as will appear from the following description.

I shall now describe the needle guard embodying my invention illustrated in the accompanying drawings and shall thereafter point out my invention in the appended 50 claim.

Figure 1 is a side elevation of the needle guard of my invention in operative position upon the presser foot bar of a sewing machine.

Figure 2 is a front elevation of the same 55 as viewed from the right in Figure 1.

Figure 3 is a horizontal section on a plane indicated by the line 3—3 of Figure 1 as viewed from above with the needle bar and 60 needle omitted.

Figure 4 is a view similar to Figure 1 with parts omitted, and further shows in broken lines one of the guard members held at the elevated non-guarding position.

The sewing machine, parts of which are 65 illustrated in the drawings, is of a type quite commonly employed in garment factories, although other types are in use, and comprises a head 1, a needle bar 2, a needle 3, a presser foot bar 4 and a presser foot 5 70 pivoted by means of a pivot pin 6 upon the lower end of a flat presser foot shank 7, the upper end part of which is removably secured in the bifurcated lower end of the pressure foot bar 4 by means of a retaining 75 screw 8. It is understood of course that the presser foot may be of a different construction and that it may be secured to the presser foot bar in a different way, as is commonly 80 the case, these matters having nothing whatsoever to do with my invention, other than that the guard device of my invention is adapted to be employed in connection with any style of presser foot. And also it is to be understood that the needle bar, such as 2, 85 may be spaced more or less from the presser foot bar 4 and that either a single needle, as shown, or a plurality of needles, as is well known in the art, may be employed. The 90 particular sewing machine shown in the drawings is adapted for either straight or zigzag stitching, and therefore, to provide for the lateral movement or throw of the needle in zigzag stitching, the presser foot 5 is provided with a transversely elongated 95 opening or slot 9. In practice it has been found that the operator will get her finger under the needle more often in zigzag stitching than when the stitching is in a straight line, this probably being due to the greater 100 width of the space or double path in which the needle alternately reciprocates.

The needle guard embodying my invention shown in the drawings comprises a supporting member in the form of a split clamp 105 10 adapted by means of a screw 11 to be clamped firmly upon the presser foot bar 4 above the shank 7 of the presser foot 5. The

supporting clamp 10 at the front thereof is provided with projecting lugs 12, to which are loosely pivoted by means of rivets 13, the upper ends of a pair of sheet metal 5 guard members 14 for free pivotal movement upon the pivots 13. As a feature of my invention these guard members 14 are so shaped and disposed as effectively to exercise their guarding function while 10 freely admitting light and permitting unobscured vision of the work at the stitching point. Along their forward edges the sheet metal guard members 14 extend forward and downward on substantially a semicircular 15 curve to a point just above and inward from the forwardly projecting upturned toes of the presser foot 5, as is shown in full lines in the drawings.

This is the operative or guarding position 20 of the guard members 14, and they are prevented from dropping below this position into contact with the presser foot 5 or into contact with the work which moves beneath the presser foot, by means of flange-like 25 abutment projections 15 formed upon the inner sides adjacent to the lower edges of the respective pivot lugs 12 of the supporting clamp 10, as shown in Figure 4. When a guard member 14 is raised, as shown in 30 broken lines in Figure 4, for the purpose of gaining access to the needle for threading the needle or for changing needles, this guard member 14 is prevented from being turned over too far towards the back, in 35 which case it might remain in that position. The upper end of each guard member 14 is provided, as shown in Figure 4, with a square upper corner 16, which in this elevated position of the guard member comes 40 into contact with the abutment stop 15, thereby effectively assuring the return of the guard members 14 to the guarding position by reason of their own weight.

For further assuring the return and the 45 maintaining of the guard members 14 at the guarding position and effectively to prevent their up and down jumping or vibratory movement, which otherwise would take place owing to the vibration of the sewing machine in operation, coiled retractile 50 springs 17 are connected to the pivot lugs 12 at the lower edges and forward ends thereof and extend forward and downward and are connected to the curved guard members 55 14, the arrangement being such, as is clear from the drawings, particularly from Figure 4, that these springs 17 will be adapted to assist gravity in returning the guard members 14 from the elevated position thereof indicated in Figure 4 to the guarding position 60 shown in full lines in all of the figures of the drawings, and these springs 17 will maintain these guard members 14 securely at this guarding position and will prevent 65 their bouncing up or vibrating when the

sewing machine is operating. When the guard members 14 are in the raised position they may be conveniently held in this position by one of the fingers of the operator, as is indicated in Figure 4. 70

In order effectively to perform their guarding function, the lower ends of the guard members 14 are widened into a substantially triangular shape, providing, as shown in the drawings, a front guard bar *a*, 75 a lower guard bar *b*, and a rear guard bar *c*, within which is formed a substantially triangular light-admitting opening 18. Between their ends or at intermediate points thereof, the sheet metal guard members 14 80 are bowed laterally outward, as is clearly shown in Figures 2 and 3, for thereby providing a clear view of the work at the stitching point, by the operator. The lower ends of the guard members 14 at the front (that is, at the rounded corner formed by the guard bars *a* and *b*) are curved inward and brought sufficiently close together to prevent the entrance between them of the finger of the operator, and are also brought close 85 enough down to the work and to the prongs of the presser foot 5 to prevent the entrance of the finger of the operator beneath the guard members at this point. It is to be noted that the operator has a clear view of 90 the work as it moves forward to the stitching point, as will be evident by a comparison of Figure 2 and Figure 3.

All parts of the guard device are preferably made of steel. Properly hardened steel 100 is particularly suitable for the guard members 14 in order that they shall be sufficiently rigid and resilient to prevent their being bent out of shape and away from their guarding position. 105

The widened lower ends of the guard members 14 at the rear thereof (that is to say, at the lower rear rounded corner formed at the junction of the lower guard bar *b* and the rear guard bar *c*) are spaced apart 110 both for the purpose of providing clear and extended vision by the operator and also to provide plenty of room for the needle bar 2 and needle 3, particularly, as in the machine shown in the drawings, when the needle bar 2 together with the needle 3 carried thereby is adapted to have a lateral throw, as above mentioned, for making a zigzag stitch, this spacing apart of the guard members at this point being clearly shown in the 115 drawings in Figures 2 and 3. The general shape of the curved sheet metal outwardly bowed guard members 14 is such that the space between these members flares both upwardly and to the front, thereby providing 120 the operator a better view of the work without in any respect interfering with the safety or guarding function of these members, and as will be clear by comparing Figures 2 and 3 of the drawings. It is to be 125 130

noted that the gradual forward and downward curve of the forward and upper edges of the guard members 14 present an even and smooth surface to the eye of the operator without any sharp corners or points projecting towards her, it having been found by experience that such projection of ends or points, which has sometimes been present in other guard devices, has had the effect of 5 disconcerting, annoying and irritating the operator, by the effect produced upon her eyes as she looks at the work, and has caused the operator to refuse to use the guard device, but instead to remove it or to push it 10 to one side. The shape or contour of the guard members 14 is such, as above described, and as clearly illustrated in the drawings, that these members while effectively performing their safety or guarding 15 function, at the same time do not in any manner interfere with the light nor with the vision of the operator, nor in any manner interfere with her operation of the machine, nor annoy her, as has been the case 20 with guard devices heretofore. The large substantially triangular opening 18 is of particular utility in freely admitting light 25 to the work at the stitching point. No matter from what direction the light may come, 30 the construction of the guard members 14 is such that no shadow will be cast upon the work at or adjacent to the stitching point. For threading the needle or changing the needle it is usually only necessary to raise 35 up one of the guard members 14 at a time, and of course both of them may be elevated at once if desired. Depending upon the particular style of the sewing machine, the needle 3 sometimes is to be threaded from one 40 side, sometimes from the other, sometimes from the front, sometimes from the back, and the independently movable guard members 14 provide for conveniently threading the needle in any way, according to the

style of the machine. It is to be noted that 45 a free open space is provided between the upper ends of the guard members 14 all the way forward from the adjacent thin band part of the supporting clamp 10, this free space being of importance in view of the 50 fact that in some sewing machines the needle bar, such as 2, may be much closer to the presser foot bar, such as 4, than is the case in the particular machine illustrated in the drawings and also in view of the further fact that in some machines other devices belonging to the machine occupy this space, such for example, as a thread take-up, sometimes carried by the presser foot 55 bar and extending forward to a point adjacent to the needle. The complete physical separation, and consequent adaptability for independent movement, of the pivoted guard members 14 therefore is seen to be of substantial advantage. 60

It is obvious that various modifications may be made in the construction shown in the drawings and above particularly described within the principle and scope of my invention. 65

I claim:

A needle guard for sewing machines, comprising a support adapted to be clamped to the presser foot bar, guard members pivoted to said supporting member and adapted to 70 be moved to needle threading and to needle guarding positions, each of said guard members being so constructed as to present an edge which is outwardly and downwardly curved from the pivotal connection between 75 the guard members and the support, and spring tension means tending to resist the movement of the guard members to needle threading position and serving to retain the same normally in needle guarding position. 80 85

In testimony whereof, I have affixed my signature to this specification.

CHARLES SEAMAN.
